COMBINED PLATE, TUMBLER, AND UTENSIL HOLDER

Robert Lee Smith, Torrance, Calif.

Application August 29, 1955, Serial No. 37,700

Term of patent 7 years

(Cl. D44—29)

Fig. 2.

Fig. 3.

I claim:

The ornamental design for a combined plate, tumbler, and utensil holder, substantially as shown.
